UNITED STATES PATENT OFFICE

139,159

DESIGN FOR A GARMENT PRESS

Harry D. Forse, Anderson, Ind.

Application May 25, 1944, Serial No. 113,750

Term of patent 14 years

(Cl. D49—1)

To all whom it may concern:

Be it known that I, Harry D. Forse, a citizen of the United States, residing at Anderson, Indiana, have invented a new, original, and ornamental Design for Garment Presses, of which the following is a specification, reference being had to the accompanying drawings, forming a part thereof.

I claim:

The ornamental design for a garment press, as shown.

HARRY D. FORSE.
